UNITED STATES PATENT OFFICE

FLOYD R. SWITZER, OF BIRMINGHAM, ALABAMA, ASSIGNOR TO THE RIBBON NEW COMPANY, A CORPORATION OF ALABAMA

REISSUED

TYPEWRITER RIBBON REJUVENATOR

Application filed May 2, 1929. Serial No. 359,983.

My invention relates to a device for rejuvenating and extending the useful life of a typewriter ribbon and ribbons of similar apparatus and has for its object the provision of apparatus of the character designated which shall be simple of design and construction, economical to manufacture, and which shall be effective to furnish an even supply of moistening fluid to a ribbon throughout the length thereof and thereby greatly extend the useful life of a ribbon.

A further object of my invention is to provide a small, easily manipulated device which may be readily employed from time to time as occasion requires, to moisten a typewriter ribbon with a proper solution, and which shall be effective to evenly distribute the moistening fluid throughout the ribbon without an excess at any one point which would cause the ink to spread and the impressions of the type to be blurred.

It is well known that the ink in typewriter ribbons in use soon dries out to such an extent that the impressions of the type become faint and the ribbon has to be discarded and a new one supplied. It is also well known that this occurs when only a small percentage of ink in the ribbon has been used up. Attempts have been made heretofore to apply to the ribbon a suitable ink solvent which would remoisten the ribbon and make available a larger percentage of the ink supply therein but great difficulties have been encountered in carrying out such an application in the way of supplying a uniform amount of the moistening fluid to the ribbon throughout its length. I have found that unless the ribbon be thoroughly and uniformly moistened throughout its length the impressions made from the type are uneven in appearance, varying from a faint impression where the moistening is inadequate, to blurred impressions where there is an excess of moistening fluid.

These and other difficulties are overcome by my invention and I accomplish a uniform distribution of the moistening fluid throughout the typewriter ribbon so that type impressions of uniform appearance are obtained from the ribbon and its useful life

multiplied many times over what it would have been without the use of my device. In accordance with my invention I provide a wick of felt or other equivalent material which is adapted to bear against the typewriter ribbon and provide means whereby the wick is impregnated or saturated with an even supply of moistening fluid in the nature of an ink solvent and this degree of saturation appears to remain substantially constant while the ribbon is drawn from end to end thereof over the wick so that the fluid is applied to the ribbon uniformly. When this is done, the type impressions made with the ribbon are uniform and not blurred. The even supply of moistening fluid to the wick is provided by means of a reservoir packed with loose fibrous material which is saturated with the moistening fluid and which bears against the wick, so that the supply is carried to the wick by capillary attraction. In addition, I employ a filling column extending upwardly from the reservoir whereby the force of gravity aids the capillary attraction in supplying the wick. A convenient manually operable means is embodied in the device for holding the ribbon against the wick with a uniform pressure when the device is in use.

A device embodying features of my invention is illustrated in the accompanying drawings, forming a part of this application, wherein

Fig. 1 is a side elevation, partly in section, of my improved device;

Fig. 2 is a rear elevation of the same;

Fig. 3 is a vertical sectional view drawn to an enlarged scale; and

Fig. 4 is a transverse sectional view taken along the line IV-IV of Fig. 3.

Referring to the drawings for a better understanding of my invention, my improved moistening device comprises a reservoir 10 having an open side 11. Fitting within the open side 11 is a frame structure 12 which serves to retain a wick 13 made of felt or equivalent material. The reservoir 10 is packed with loose fibrous material 14 which material bears against the wick 13 on the inside of the reservoir.

Extending upwardly from the reservoir 10 is a filling column 16 provided with a screw cap 17, the column 16 being also packed with the loose fibrous material. The packing 14 which extends up into the filling column is saturated with a suitable moistening fluid in the nature of an ink solvent. The fluid in the column 16 is aided by gravity in its capillary flow through the fibrous material and into the wick 13. The quantity of fluid supplied is never enough to create a running or dripping of the fluid, but only sufficient to saturate the wick.

I have found that a fluid comprising substantially 85% mineral seal oil, 6% neat's-foot oil, 4% glycerine and 5% methyl salicylate or oil of bergamot to be a suitable moistening fluid.

With the apparatus described, I have found that if a typewriter ribbon, shown at 18, is brought to bear against the saturated wick 13 in the open face of the reservoir 10, and the ribbon is drawn from end to end across the wick, a uniform supply of moistening fluid is distributed to the ribbon throughout its length. In order that the ribbon 18 may be held against the wick 13 with an even pressure, I provide a plate 19 hinged to the upper edge of the reservoir 10 at 21 and provided with an upwardly extending finger piece 22 which latter is pressed forwardly by a spring 23. In use the ribbon 18 is placed under the plate 19 as shown in the drawings and is drawn across the wick. In manipulating the device, the filling column 16 also serves as a convenient handle, and being adjacent the finger piece 22, the plate 18 is easily operated to place it over a typewriter ribbon.

While I have shown my invention in but one form, it will be obvious to those skilled in the art that it is not so limited, but is susceptible of various changes and modifications, without departing from the spirit thereof, and I desire therefore that only such limitations shall be placed thereupon as are imposed by the prior art, or as are specifically set forth in the appended claims.

It is understood that the term "typewriter" ribbon, as employed in the specification and claims, is intended to apply to equivalent apparatus employing an inked ribbon to obtain type impressions.

What I claim is:

1. A typewriter ribbon moistener comprising a reservoir having an opening in one side thereof and being packed with loose fibrous material saturated with a moistening fluid, a relatively flat wick of close fibrous material disposed across the opening, and a spring pressed plate hinged across the opening and adapted to press the typewriter ribbon against the wick.

2. A typewriter ribbon moistener comprising a reservoir having an opening in one side thereof and being packed with loose fibrous

material saturated with a moistening fluid, a relatively flat wick of close fibrous material disposed across the opening, a spring pressed plate hinged across the opening and adapted to press the typewriter ribbon against the wick, and a filling column extending upwardly from the reservoir and having a packing of loose fibrous material saturated with a moistening fluid and bearing against the wick.

3. A portable moistener for typewriter ribbons comprising a reservoir having an opening in one side thereof and being packed with loose fibrous material saturated with a moistening fluid, a filling column extending upwardly from the reservoir and also packed with the loose fibrous material, a spring pressed plate covering the opening and hinged to the upper side thereof, said plate being adapted to press the ribbon against the open side of the reservoir, a finger piece for the plate extending alongside the filling column and a felt wick disposed across the opening in the side of the reservoir and bearing against the loose fibrous material on one side and the wick on the other.

In testimony whereof I affix my signature.

FLOYD R. SWITZER.
